UNITED STATES PATENT OFFICE.

HENRY HORSTMAN, OF KEARNEY, NEBRASKA.

BRACKET.

Application filed October 4, 1922. Serial No. 592,330.

To all whom it may concern:

Be it known that I, HENRY HORSTMAN, a citizen of the United States, residing at Kearney, in the county of Buffalo and State 5 of Nebraska, have invented a new and useful Bracket, of which the following is a specification.

This invention relates to a supporting bracket or collapsible bench.

10 The object of the invention is to provide a support of this character which is especially constructed for use in supporting drawing boards and the like and which may be folded up and laid aside when not in use, 15 taking up very little space.

With the foregoing and other objects in view which will appear as the description proceeds, the invention resides in the combination and arrangement of parts and in 20 the details of construction hereinafter described and claimed, it being understood that changes in the precise embodiment of the invention herein disclosed may be made within the scope of what is claimed without deviating from the spirit of the invention.

In the accompanying drawings:—

Figure 1 represents a plan view of the bracket constituting this invention shown in operative position.

30 Figure 2 is a side elevation thereof shown in operative position in full lines and in dotted lines in the position assumed when being folded.

In the embodiment illustrated, a skeleton 35 top 1 is shown composed of side bars 2 and 3 connected by cross bars 4, 5 and 6, spaced longitudinally apart, bar 4 being arranged at one end of the side bars 2 and 3 and bar 6 spaced inwardly from the opposed ends 40 thereof.

A leg 7 is hingedly connected at one end to the intermediate cross bar 5 on the lower face thereof as shown at 8 and has an opening 9 formed therein intermediate its ends 45 preferably about midway thereof.

A brace 10 is hingedly connected at one end to the lower wall of the opening 9 as shown at 11, and at its other end to the cross bar 6 midway its ends as shown at 50 12.

This brace 10 is made in two sections 13 and 14 hingedly connected at their inner

ends as shown at 15, being designed to break upwardly as shown in dotted lines in Fig. 2 to provide for folding of the brace when the bracket is not in use. 55

In the use of this support, it is opened up into the position shown in Fig. 1 and is designed to be mounted in a bench vice (not shown), and a drawing board or other object may be supported on the skeleton top 1 60 thereof. This support is intended to take the place of the expensive desks which are used in mechanical drawing departments of high schools and colleges, which schools are equipped with wood working benches having 65 vices of this character.

When the bracket is not in use, the brace 10 is broken at the connection of its hinged sections and these sections are folded in superposed relation while the leg 7 folds 70 flat against the lower face of the top 1. It will thus be seen that this bracket when not in use will occupy a very small space and may be quickly set up for use when desired, adapting it especially for use in schools or 75 other places where space is restricted.

The meeting ends of the sections 13 and 14 of the brace 10 are arranged to abut when the sections are opened as shown in full lines in Fig. 2, which prevents the brace 80 from collapsing, which is due to the fact that the hinge 15 is arranged on the outer faces of the sections.

I claim:—

An article of the class described comprising a table top rigid throughout its area and having a supporting leg pivotally connected to its lower face midway its ends, said leg having an opening therein, a brace member hinged at one end to the lower face of said 90 top near one edge and at its other end to said leg inside the opening, said brace being composed of hingedly connected upwardly breakable sections, said sections being rigidly held when in open position. 95

In testimony that I claim the foregoing as my own, I have hereto affixed my signature in the presence of two witnesses.

HENRY HORSTMAN.

Witnesses:

J. A. WALLACE,
ARTHUR R. GREEN.
